UNITED STATES PATENT OFFICE.

WILLIAM T. BARNUM, OF CHICAGO, ILLINOIS.

PORTRABLE LAMP.

1,412,036.

Specification of Letters Patent. Patented Apr. 11, 1922.

Application filed March 21, 1921. Serial No. 454,040.

To all whom it may concern:

Be it known that I, WILLIAM T. BARNUM, a citizen of the United States, residing at Chicago, in the county of Cook and State 5 of Illinois, have invented certain new and useful Improvements in Portable Lamps, of which the following is a specification, reference being had to the accompanying drawings, and to the reference characters marked 10 thereon, which form a part of this specification.

This invention relates to improvements in portable lamps, which include a parabola shaped metallic reflector and a high power 15 incandescent lamp bulb filled with nitrogen or other inert gases.

In many cases, it is inconvenient or inexpedient for photographers to use a flash light and it is necessary for lighting the subjects to be photographed at night or in places where daylight is inaccessible, to use a parabolic reflector containing a high powered electric light. These are sometimes mounted upon a tripod or other fixed support. It is 20 often necessary, however, to use the reflector-lamp in the hands of the operator, to particularly direct the light to a given spot or to direct the light rays where desired by moving the lamp to and fro during the exposure of the camera so as to project the light into deep crevices, to soften set shadows and otherwise promote the handicraft of the 25 photographer.

The heat generated in these high powered 30 lamps makes the handling of the same a matter of great inconvenience unless the reflector is provided with a long and insulated handle. Such handles are exceedingly awkward, and frequently, by their mere size 35 and position and shape, prevent the best and most desirable use of the lamp.

The principal object of my invention is to provide a portable lamp comprising a parabolic metal reflector, of exceedingly 40 light metal, and having a high powered incandescent bulb, with an air-cooled handle 45 made of metal and so shaped and arranged as to form a support for the incandescent bulb, and at the same time be convenient at 50 all times for the purposes intended.

Another object of the invention is to provide this air cooled handle with means whereby the lamp, as a unit, may be removably and adjustably mounted upon a fixed 55 support, such as the familiar photographers' tripod.

Another object of the invention is to provide a pivoted arm to be used in connection with the air cooled handle, adapted to be swung on either side of said handle, so that 60 together with the handle and the rim of the reflector, there will be three points of contact for the lamp when resting upon a fixed surface, such as a table or floor, it being frequently necessary to set the portable lamp 65 down upon a table or the floor and have it remain in a certain position to cast a steady light upon the subject being photographed.

With the foregoing objects in view, my invention consists in the devices and combinations of devices illustrated, described and herein claimed.

In the drawings:

Fig. 1 represents a lamp constructed in accordance with my invention, the same being a rear elevation with the lamp resting upon a flat surface.

Fig. 2 represents the lamp in side elevation, attached to a fixed support, such as a tripod.

Fig. 3 is a central vertical sectional view, showing the bulb supported in the lamp socket of the handle.

Fig. 4 is a top plan view, enlarged, of the attachment for the handle, and means for adjusting the same.

Fig. 5 is a side elevation of the same on the same scale.

Fig. 6 is a horizontal sectional view showing a detail.

In the drawings, a high powered incandescent bulb is indicated by the letter A, its shank 1 being adapted for connection with a lamp socket 2. The lamp socket 2 is of any conventional shape or construction, and carries the electric cable 3 adapted to be connected with a source of electrical energy. As neither the bulb nor the socket, per se, constitute any part of the invention except as in combination with the other parts of 100 the device, it is unnecessary to further describe the same.

The lamp socket 2 is located in and secured to the lower end of the metal handle 4, attached by suitable rivets 5 to a metallic reflector 6, parabolic in shape and terminating with a finished beaded margin 7. The reflector 6 is preferably made of aluminum, as is also the handle 4. It will be observed particularly by reference to Fig. 3, that 110 the handle 4 is tapered, its smaller end being that to which the socket 2 is secured,

and its larger end being that riveted to the reflector 6. At a point above where the lamp socket is attached, and spaced upwardly at proper intervals throughout the length of the handle, I have made a plurality of rows of large and small apertures 8 and 9. It will also be noticed by reference to Fig. 3, that the shank 1 of the bulb or lamp A is substantially cylindrical throughout its length and thereby affords a very considerable air space, indicated by the letter S, between said shank 1 and handle 4. I have found that by providing this air space S in the handle, and by providing a plurality of air holes or apertures in the handle, that it does not become heated, but merely warm, and that the device as a whole may be very comfortably and conveniently handled, without a glove or other protective covering, notwithstanding the fact that the metallic reflector 6 will be almost too hot to touch.

On the outside of the handle 4, I place a ring 10, the same consisting of a band of metal provided at each end with a lug 11 and a screw 12. By this means, the band 10 may be firmly, although removably, secured to the upper part of the handle 4. Projecting upwardly from the band 10 is a short standard 13. A metal bar of flat metal 14, approximately as long as the handle 4, is pivotally mounted at 15 to the standard 13. This bar 14 may be swung to the right or left of the standard 13 as indicated in dotted lines in Fig. 5. The lower end of the handle 4, a portion of the beaded margin 7 of the reflector 6 and the lower end of this bar 14 form three points of support, when it is necessary to place the lamp as a whole upon a support such as a table or the floor. This is indicated clearly in Fig. 1, where in full lines the arm 4 is shown as thrown to the right, and where in dotted lines the arm is indicated as thrown to the left of the arm.

When it is desired to mount the lamp upon a fixed support, such as a tripod, I make use of an adjustable attachment secured to the band 10. This attachment is as follows: A metallic frame-like structure 16 is loosely mounted upon a stud 17. The stud is riveted to a ring 10 so as to project laterally therefrom, as shown more clearly in Fig. 6. Surrounding the stud 17 and between the frame 16 and the ring 10, is a disc member 18, made rigid with the ring 10 by soldering or other convenient means. Passing through the two side walls of the frame 16 is an adjusting screw member or bolt 19, adapted to engage a clamping nut 20. The nut 20 is of sufficient size to overlie the peripheral margin of the disc 18 so that when the thumb piece 21 of the bolt 19 is turned, the nut 20 will clamp the disc 18 closely against the side wall of the frame 16 and thus hold the frame structure with respect to the ring 10 in that position in which it happens to be when the clamping action occurs. Projecting downwardly from the frame 16 is a pivotal stud or bolt 22 adapted to enter a suitable recess in the upper end of a tripod section 23. A thumb screw 24 in said tripod section 23 is adapted, in a familiar manner, to have its end bear against the stud 22, and thus lock the stud 22 and the tripod 23 together.

When the device as a whole is placed upon a tripod, the lamp may be swung in a horizontal plane into the desired position, and then locked in said position, the stud 22 turning on its axis in the tripod section 23 until the desired position is attained, when it is locked in that position by the thumb screw 24. Similarly, any angular position, with respect to the tripod, may be given to the lamp as a whole, by loosening the thumb screw 19 and moving the lamp; in such case the lamp with the stud 17 pivots in the frame 16 until the desired angular position is attained, when the parts are locked together by turning the screw 19.

It will thus be seen that adjustment may be made vertically and horizontally, as desired. Changes in the details of construction may be made without departing from the spirit of my invention, but the forms here shown are recommended as simple, cheap and highly efficient.

I claim as my invention:

1. A portable lamp comprising a reflector of thin, light metal and an elongated handle also of thin, light metal projecting radially therefrom, a lamp socket in the handle, a lamp provided with a shank, the latter extending into the handle and secured to said socket, the walls of the handle being spaced from the lamp shank and a plurality of apertures through the handle.
2. A portable lamp comprising a reflector of thin, light metal and an elongated handle also of thin, light metal projecting radially therefrom, with its ends extending beyond the margin of the reflector, a lamp socket in the handle and a lamp provided with a shank, the latter extending into the handle and secured to said socket, the walls of the handle being spaced from the lamp shank and a plurality of apertures through the handle.
3. A portable lamp comprising a reflector of thin, light metal, an elongated tubular handle of similar metal projecting radially therefrom with its ends projecting beyond the margin of the reflector, a lamp socket in the handle end, a lamp in the reflector having its shank projecting through the handle to engage said socket, the walls of the handle being apertured throughout its length and of an interior diameter to form a substantial air space about the lamp shank.
4. A photographer's portable lamp com-

prising a thin, light, metal reflector, a tapered handle of similar metal projecting radially therefrom to a distance beyond the rim of the reflector, a lamp socket in the 5 end of the handle, a lamp in the reflector having its shank project through the handle to and secured in the socket, an air chamber in the handle, surrounding the shank, increasing in size towards the reflector, and a 10 plurality of apertures in the handle wall throughout its length.

5. A portable lamp comprising a reflector of thin, light metal and an elongated handle also of thin, light metal projecting radially 15 therefrom, a lamp socket in the handle, a lamp provided with a shank, the latter extending into the handle and secured to said socket, the walls of the handle being spaced from the lamp shank and a plurality 20 of apertures through the handle, a band on the outside of the handle and a metal bar pivotally or hingedly secured to the band, the handle and the bar being of suitable length to cooperate with the rim of the 25 reflector to form three points of contact with a suitable rigid support.

6. A portable lamp for photographers' use comprising a parabola-shaped reflector of thin, light metal, an air cooled hollow 30 handle of similar metal projecting radially therefrom, a lamp, means within the handle for supporting the lamp, means upon the outside of the handle for removable and adjustable attachment with a rigid support.

35 7. A portable lamp for photographers'

use comprising a parabola-shaped reflector of thin light metal, an air cooled hollow handle of similar metal projecting radially therefrom, a lamp, means within the handle for supporting the lamp with its bulb in the 40 reflector, means upon the outside of the handle for removable attachment with a rigid support, said means including a circumferential band, a supporting stud and operative connections between said stud and 45 said band.

8. A portable lamp for photographers' use comprising a parabola-shaped reflector of thin light metal, an air cooled hollow handle of similar metal projecting radially therefrom, a lamp, means within the handle for supporting the lamp with its bulb in the reflector, means upon the outside of the handle for removable attachment with a rigid support, said means including a circumferential band, an outwardly projecting pin 50 thereon, a frame having journal bearings for said pin, a supporting stud secured to said frame, and means for locking the projecting pin to the frame in any desired position. 55

In testimony that I claim the foregoing as my invention I affix my signature in the presence of two witnesses, this 18th day of March, 1921.

WILLIAM T. BARNUM.
